UNITED STATES PATENT OFFICE

MANUEL V. PEREZ AND JOHN PETE RAMBAUD, OF MIAMI, ARIZONA

COMBINATION LOCK

Application filed November 19, 1928. Serial No. 320,474.

This invention relates to locks, and its general object is to provide a permutation lock that is primarily designed for doors of buildings and the like, and includes a bolt controlled by tumbler operated means, as well as other means manually operated from both sides of a door when the tumbler operated means is in its inoperative position.

Another object of the invention is to provide a permutation lock of the character set forth that is designed in such a manner that the combination thereof can be changed in an easy and expeditious manner.

A further object of the invention is to provide a lock that can be disposed to operative position from the inner side of the door carrying the lock when the permutation feature thereof is in its inoperative position.

A still further object of the invention is to provide a lock that includes means for securing the permutation features thereof against movement when it is not desired to use the same.

Another object of the invention is to provide a lock including a permutation means that has audible indicating means that sound upon movement of the knob for operating the permutation means, with the result the lock can be operated in the dark by one familiar with the combination, as the indicating means is timed with respect to the movement of the numeral bearing disk.

A further object of the invention is to provide a lock of the character set forth that is ornamental in appearance, rather simple in construction, inexpensive to manufacture and install, and efficient in operation and service.

This invention also consists in certain other features of construction and in the combination and arrangement of the several parts, to be hereinafter fully described, illustrated in the accompanying drawings and specifically pointed out in the appended claims.

In describing our invention in detail, reference will be had to the accompanying drawings wherein like characters denote like or corresponding parts throughout the several views, and in which:

Figure 1 is a fragmentary inner side view of the lock forming the subject matter of the present invention and showing the same applied to a door.

Figure 2 is a vertical longitudinal sectional view taken through the lock and the casing thereof as shown in Figure 1.

Figure 3 is a sectional view taken approximately on line 3—3 of Figure 2, looking in the direction of the arrows.

Figure 4 is a fragmentary detail view showing the tumbler operating stud carrying plate and the sound producing structure.

Figure 5 is a top plan view of the structure as shown in Figure 4.

Figure 6 is a sectional view taken approximately on line 6—6 of Figure 3, looking in the direction of the arrows.

Figure 7 is a sectional view taken approximately on line 7—7 of Figure 6, looking in the direction of the arrows.

Figure 8 is a sectional view taken approximately on line 8—8 of Figure 3, looking in the direction of the arrows.

Figure 9 is a detail view of one of the tumblers.

Figure 10 is a similar view of the other tumbler.

Referring to the drawings in detail, the letter A indicates a door to which is secured a lock constructed in accordance with our invention.

The lock includes inner and outer escutcheon plates 1 and 2, and formed with the plate 1 and extending through the door is a sleeve 3 which is received in an opening formed in the plate 2, and surrounding this opening is a collar 4 formed integral with the plate 2.

Secured to the inner plate 1 is a casing 5 which includes a relatively large portion for the purpose of housing a portion of the parts cooperating with the bolt of the lock, and said casing also has formed therewith a portion 6 provided with apertured ears 7 adapted to receive screws or like securing means for fixing the casing to the door in the manner as illustrated in Figure 1. The portion 6 is hollow and is formed with a slot through which is slidably mounted the head 8 of the

locking bolt. The head 8 is beveled in the usual manner to provide a cam surface and has formed therewith a shank 9 slotted as at 10, with a stud 11 extending in the slot and from the head 8 as best shown in Figure 2.

5 A band 12 is shaped to follow the shape of the relatively large portion of the casing 5 and this band surrounds a portion of the bolt operating means as well as a portion of 10 the permutation means of our lock. The ends of the band however terminate in spaced relation at the juncture of the portion 6 of the casing and the shank 9 of the bolt is movable between these ends as best shown in Figure 2.

15 Confined within the area enclosed by the band is a projection 13 extending outwardly from the plate 1 and surrounding said projection 13 is a collar 14 having extending therefrom in alignment with the stud 11 a 20 like stud 15, and these studs 11 and 15 receive a coil spring 16 which is adapted to normally retain the bolt in its outer position as shown.

25 The bolt can be operated from either side of the door when it is not held against movement, and for this purpose we provide outer and inner plate members 17 and 18 each of which include housings 19 and 20. These 30 housings have pivotally secured therein latch members 21 in the form of bell crank levers and these latch members have one arm extending through slots formed in the housings 19 and 20 while the opposite arms thereof have their free ends disposed in contacting 35 engagement with plates 22 mounted for slideable movement between guides 23. Each of the plates 22 have formed in their upper ends slots 24 and mounted in one of these slots is the stud 25 formed on one end of a bell crank 40 lever 26 which has a stud on its opposite end for engagement with the arm 27 of a like shape lever 28. The opposite arm of the bell crank lever 28 is arranged in engagement 45 with a roller 29 mounted for rotation on a stud carried by the inner end of the shank 9 of the locking bolt as best shown in Figure 2 of the drawings.

50 Formed with the plate 1 and passing through the door is a sleeve 30 which has mounted for rotation therein a shaft 31 having secured to its outer end which as shown in Figure 3 projects into the housing 20, a stud carrying member 32, and the stud of said member 32 is disposed in the slot of the 55 plate 22 arranged in the housing 20.

56 The bell crank lever 26 is secured to the end of the shaft 31 that projects into the casing 1, and by this construction, it will be apparent that pressure upon either of the latch members 21 will retract the locking bolt. We also provide bail handles 33 disposed directly below the housings 19 and 20, so that by gripping the handles, little difficulty will be experienced in moving the latch members with 60 the thumb of the hand gripping the handles.

The locking bolt can be secured in its retracted position and the shank of the bolt has formed therewith a projection 34 extending laterally therefrom as shown in Figure 2. Mounted in the casing is a guide member 35 70 which accommodates a plate 36 for slidable movement therein and this plate 36 has rising therefrom an extension 37 adapted to be positioned in the path of the projection 34 for holding the locking bolt in its retracted position. The plate 36 is operated from the inner side of the lock through the instrumentality of a handle 38 which has a shank passing through the casing and secured to a button 39 laterally of its center, and to one side 75 thereof, while extending from the opposite side and eccentrically arranged with respect to said button is a stud 40 which is disposed in a slot 41 formed horizontally in said plate 36. By this construction, it will be obvious 80 that movement of the handle 38 will raise and lower the plate 36 for positioning the extension 37 into and out of the path of the projection 34.

85 The permutation feature of the lock operates to prevent movement of the bolt when the latter is in its operative position as shown and includes a stem 42 that is square in cross section and said stem passes through the sleeve 3 and has a portion extending into the collar 4 as shown in Figure 3. The stem has fixed to its extending portion a numeral bearing disk 43 which has formed therein inwardly of the numerals 44 a plurality of openings 45 arranged in circular formation as best 90 shown in Figure 8, and disposed between each of the numerals which we have shown as being 1 to 6 inclusive, is an opening 46. These 95 openings 46 act in the same capacity as the numerals, and extending from the top of the collar 4 is an index pointer 47 which cooperates with the openings 46 and numerals 44 100 for working the combination of the permutation structure as will be apparent.

105 Secured to the inner side of the stem 42 is a disk plate 48 having a corrugated edge forming recesses 49 and these recesses are twelve in number to correspond to the total number of the numerals 44 and openings 46. Fixed to the plate 1 through the medium of a screw 110 passing through a strip 50 is a spring member 51 which terminates in a reduced end 52 of a shape corresponding to the recesses 49 and this reduced end is adapted to be received in the recesses as clearly shown in Figure 4 of the drawings.

115 By this construction, it will be apparent that when the disk plate 48 is rotated, the reduced end will be disposed from one recess to the other which will cause a clicking sound as the projections of the corrugated edge engage the reduced end, with the result a person 120 can operate the lock in the dark if the combination is known to that person as the clicks 125 130

will be the equivalent of seeing the openings 46 and numerals 44.

Extending outwardly from the disk plate 48 are pins 53 and formed with said plate 48 is an arm 54 which is disposed at an outward inclination for a portion of its length and terminates in a straight free end as best shown in Figure 5.

As previously set forth, the recesses 49 correspond in number to the total number of the numerals 44 and openings 46, and these recesses are disposed in alignment with the numerals 44 and openings 46 with the result the combination can be worked by listening 15 to the clicks. When it is desired to change the combination for opening the lock, the casing 5 can be removed and due to the fact that the disk plate 48 is secured to the stem 42 through the medium of a screw as best 20 shown in Figure 3, this screw can be loosened and the disk plate 48 moved as desired. When the disk plate has been moved to change the combination, the screw is then tightened up and a new combination has been 25 provided.

Extending inwardly from the casing 5 and secured thereto is a headed pin 55 having mounted thereon tumblers which are indicated by the reference numerals 56 and 57. 30 Each of the tumblers are formed with recesses 58 and extending from the periphery of one of said tumblers is a tongue 59. The tumblers are further provided with lugs 60 which also extend from the peripheries thereof in a manner whereby when these lugs are 35 in contacting engagement, the recesses of one of the tumblers will be disposed out of registration with the recesses of the other. Arranged between the tumblers 56 and 57 and surrounding the headed pin 55 is a spring 40 washer 61 which normally retains the tumblers in spaced relation as best shown in Figure 3 of the drawings. Plain washers 62 are secured to the headed pin and arranged upon the outer sides of the tumblers.

Surrounding the headed pin 55 is a flat ring member 63 having arranged therein a slot 64 for the purpose of accommodating the free end of the arm 54 which is adapted for 45 rotating the ring member. Formed in the casing and arranged therein in row formation as shown in dotted lines in Figure 2, are arcuate shape slots 65 through which are passed pins 66 for connecting the ring member 63 with a disk 67 mounted for rotation 50 on the outer side of the casing 5 as shown in Figure 1 of the drawings. The disk 67 has secured thereto and extending outwardly therefrom a finger piece 68 whereby this disk 55 may be moved from the inner side of the door 60 for moving the ring member accordingly.

The disk plate 48 has formed in its periphery a recess 69 and secured to the plate 1 to be disposed in the path of the plate 48 is a 65 finger 70 which prevents movement of the

plate 48 toward the tumblers for operating the latter until the recess 69 is disposed in registration with the finger 70 as shown in Figure 4 of the drawings. The disk plate 48 is movable in a direction toward and from the tumblers through the medium of the stem 42 which is slidably mounted in the sleeve 70 3. This movement is accomplished by a knob 71 having extending from the inner side thereof a pin 72 adapted to be received in one of the openings 45 so that the knob which is secured to the outer end of the stem rotates the numeral bearing disk 43 in accordance with the disk plate 48.

Formed with the ring member 63 is an arcuate shape arm 73 and this arm extends from the periphery of the ring member and is adapted to be received for slidable movement in a bracket 74 formed with and rising from an obstruction member 75 which is mounted 80 between guide-ways 76 and is primarily designed to prevent inward movement of the bolt by being disposed in the path thereof when the bolt is held against movement by the permutation feature of the lock. It will 85 be apparent that upon rotation of the ring member in one direction, the obstruction member 75 will be lowered for disposal in the path of the shank 9 and when rotated in an opposite direction, it will be raised to 90 the position as shown in Figure 2, through the instrumentality of the arcuate shape arm 73.

The ring member is held against movement and retained in a position to hold the obstruction member out of the path of the shank, by means which includes a plate 77 having a slot 78 arranged therein and said plate is mounted for slidable movement in a guide housing 79 by a handle 80 mounted 100 for rotation in the wall of the casing and has its inner end 81 secured to a disk which has a stud eccentrically extending therefrom and received in the slot 78, with the result 105 when the handle is rotated, the plate 77 will be moved toward and away from the ring member which is provided with a recess in its periphery to accommodate a stud 82 formed with the plate 77, as best shown in 110 Figure 2 of the drawings.

When it is desired to operate the permutation feature of our lock, the handle 80 must be moved to a position for disposing the stud 82 out of the recess formed in the periphery of the ring member, the knob is then rotated 115 for positioning the first numeral or opening 46 of the combination in alignment with the index pointer 47, and when the numeral or opening is in this position, the ring of the disk plate 48 will be aligned with the finger 70 so that the disk plate 48 can be moved toward the tumblers, and further operation of the knob to the remaining numerals or openings 46 will move the tumbler 56 through the medium of the engagement of the arm 54 with 120 125 130

the tongue 59 thereof, for disposing the recesses of each of the tumblers in registration with each other for the purpose of allowing the passage of the pins 53 through the recesses and the arm 54 into the slot 64 whereby the ring member can be rotated in the manner as above set forth.

From the above description and disclosure of the drawings, it will be obvious that we have provided a lock for a door or the like that is ornamental in appearance and can be operated from both sides of the door when the permutation feature thereof is arranged to its inoperative position, and this feature can be held against operation and the door locked by the other means described.

It is thought from the foregoing description that the advantages and novel features of our invention will be readily apparent.

We desire it to be understood that we may make changes in the construction and in the combination and arrangement of the several parts, provided that such changes fall within the scope of the appended claims.

What we claim is:

1. A lock of the character described comprising a pair of escutcheon plates adapted to be secured to the opposite sides of a door, a casing secured to one of said escutcheon plates, a locking bolt mounted for slidable movement and having its shank arranged in said casing, housings secured to each of said plates, means arranged in said housings and being operably connected with said bolt for retracting the same, means for locking the bolt against movement and being operable from the inner side of said door, permutation means to prevent operation of said bolt, and being operable from the opposite sides of said door and means operable from the inner side of said door to prevent operation of the permutation means.

2. A lock of the character described comprising a pair of escutcheon plates adapted to be secured upon opposite sides of a door, a spring pressed locking bolt including a slotted shank for accommodating the spring means thereof, a casing receiving said shank, a roller secured to the inner end of said shank, operably connected bell crank levers with one of said levers having an arm arranged in contacting engagement with said roller for retracting said bolt, and means for operating said bell crank levers and being disposed upon opposite sides of said door.

3. A lock of the character described comprising a pair of escutcheon plates adapted to be secured upon the opposite sides of a door, a casing secured to one of said escutcheon plates, a locking bolt including a shank mounted for slidable movement in said casing, spring means for normally holding the bolt in extended position, means operable from opposite sides of the door for retracting the bolt against the tension of its spring

means, means for locking said bolt in its retracted position and being operable from the inner side of said door, and permutation means including an obstruction member adapted to be arranged in the path of said bolt and means for raising and lowering said obstruction member into and out of said path.

4. A lock of the character described comprising a pair of escutcheon plates adapted to be secured upon opposite sides of a door, a casing secured to one of said plates, a locking bolt mounted for slidable movement in said casing, permutation means to prevent movement of said locking bolt to its retracted position and including an obstruction member, guide means for said obstruction member, a bracket formed with said obstruction member, a ring member, means for operating said ring member upon knowledge of the combination of the permutation means, and an arcuate shaped arm formed with the periphery of said ring member and mounted for slidable movement with respect to said bracket for disposing the obstruction member into and out of the path of the shank of the locking bolt.

5. A lock of the character described comprising a pair of escutcheon plates adapted to be secured upon opposite sides of a door, a casing secured to one of said escutcheon plates, a spring pressed bolt including a beveled head, a shank for said head and extending into said casing for slidable movement therein, means for operating said bolt from opposite sides of said door, means to prevent said operation and including a plate guided in said casing, an extension formed with said plate, a projection formed with said shank and arranged whereby it is engageable by said extension when the latter is arranged in the path thereof, permutation means for preventing retraction of said bolt, and means to prevent operation of the permutation means and being controllable from the inner side of said door.

6. A lock of the character described comprising escutcheon plates adapted to be secured upon the opposite sides of a door, a casing secured to one of said plates and being disposed on the inner side of said door, a collar formed with the other of said plates, a spring pressed locking bolt including a shank mounted for slidable movement in said casing, permutation means operable to prevent retraction of said locking bolt, means for changing the combination of said permutation means, clicking means for said permutation means and being operable upon working the combination thereof, said permutation means including slidably mounted parts with one of said parts arranged in said collar and a knob for operating the permutation means and having connection with said last mentioned part as and for the purpose specified.

7. A lock of the character described comprising escutcheon plates adapted to be secured upon opposite sides of a door, a casing secured to one of said plates, a locking bolt mounted for slidable movement in said casing, spring means for retaining said locking bolt in operative position, permutation means to prevent retraction of said bolt and including an obstruction member, a bracket formed with said obstruction member, a ring member having a slot in its inner periphery and mounted for rotation on the inner side of said casing, an arm extending from the periphery of said ring member and mounted for slidable movement with respect to said bracket for disposing the obstruction member into and out of the path of said locking bolt, a stem mounted for slidable movement through said door, a knob for one end of said stem and being arranged on the outer side of said door, a disk plate secured to the inner end of said stem and provided with a corrugated periphery, spring means engageable with the corrugations and adapted to provide clicking sounds upon rotation of said disk plate, tumblers mounted for rotation in said casing and being formed with recesses, means secured to said disk plate for operating said tumblers for disposing the recesses thereof in registration, pins adapted to pass through the registering recesses for disposing the last mentioned means in said slot for operating said ring member, a combination bearing plate secured to said knob and means to prevent slidable movement of said stem upon certain positions of the disk plate and being engageable with said disk plate to prevent said movement.

In testimony whereof we affix our signatures.

MANUEL V. PEREZ.
JOHN PETE RAMBAUD.
